CLAIM

I claim the ornamental design for a pallet container, as shown and described.

DESCRIPTION

FIG. 1 is a top perspective view of the pallet container, the opposite top perspective view being identical;

FIG. 2 is a top perspective view of the pallet container showing hinged panels in an open position;

FIG. 3 is a partial bottom perspective view of the pallet container, the opposite bottom perspective view being identical; and,

FIG. 4 is a top perspective view of a pair of pallet containers, one stacked on top of another, the opposite top perspective view being identical.

The broken lines are provided for illustrative purposes only and form no part of the claimed design.

The bottom of the pallet is partially shown in FIG. 3 for convenience of illustration.
